CLAIM

We claim the ornamental design for a wall-mountable occupancy sensor, as shown and described.

DESCRIPTION

FIG. 1 is a perspective view of a wall-mountable occupancy sensor according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a wall-mountable occupancy sensor according to a second embodiment of our new design; and,

FIG. 8 is a top view thereof, the front, left side, right side, and bottom views, respectively, of the second embodiment being identical to the front, left side, right side, and bottom views of the first embodiment.

The rear views form no part of the design and are omitted.
